UNITED STATES PATENT OFFICE.

PERCY HUNT WILSON, OF NORFOLK, VIRGINIA.

FLEXIBLE SCREEN.

SPECIFICATION forming part of Letters Patent No. 769,423, dated September 6, 1904.

Application filed December 16, 1903. Serial No. 185,382. (No model.)

To all whom it may concern:

Be it known that I, PERCY HUNT WILSON, a citizen of Great Britain, residing at Norfolk, in the county of Norfolk and State of Virginia, have invented certain new and useful Improvements in Flexible Screens, of which the following is a specification.

My invention relates to that class of screens, such as are used for rolling shutters and other purposes, where a series of longitudinal strips are jointed together; and my invention consists in so constructing the said strips that the edge of one may be flexibly connected with the edge of the next strip, so as to form a self-supporting connected structure—that is, so that the connections between the strips shall be secured without the use of chains or other ancillary connecting means, as fully set forth hereinafter and as illustrated in the accompanying drawings, in which—

Figure 1 illustrates two connected strips of a flexible screen, showing the same in cross-section and in perspective. Fig. 2 is a longitudinal section at one end or edge of the structure. Fig. 3 is a detached end view of one of the strips. Fig. 4 is a transverse section illustrating another form in which the structure may be embodied.

The screen consists of a series of connected parallel strips or members A, each provided with a cylindrical rib 1 at one edge and with two inturned separated ribs 2 3 at the opposite edge, the inner contour of the ribs 2 3 corresponding to the external form of the ribs 1, so that the strips may be connected together by introducing the cylindrical rib of one strip between the inturned ribs of the next strip, as shown in Fig. 1. When thus connected, a series of strips or members will constitute a continuous jointed or flexible structure. Preferably each strip is made of thin metal to thereby reduce weight and facilitate manufacture; but when made of sheet metal there is difficulty in securing a self-supporting connected structure from the tendency of the ribs 2 3 to yield or spring apart and release the cylindrical rib from its position. To overcome this difficulty, I strengthen each strip by the use of a bent strip 4, which may be of any suitable weight required to in-

sure the desired rigidity at the socketed edge of the strip. Where the strip, as shown in the drawings, is made of metal bent to form a hollow structure and with hollow ribs 2 and 3, the strengthening-strip 4 may fit within the hollow ribs, as shown in Fig. 1. In other cases, as shown in Fig. 4, a hollow strip 4 of heavy material may be bent to receive the rib 1 and may be soldered or otherwise secured to the inturned sides 5 6 of the main strip. In either case the strengthening-strip 4 imparts such stiffness to the inturned ribs as will prevent them from springing apart and causing the separation of the different elements of the structure. In some cases it is desirable to have the faces of the strips at one side as nearly in line with each other as possible, and this may be secured by setting the ribs 1 nearer to one edge of the strip than to the other, as shown in Fig. 1. Additional rigidity may be imparted to the strips by providing each with a suitable filler. For some purposes, where a fireproof screen is not required, the filler may be made of wood or pulp; but where a fireproof screen—as, for instance, a rolling shutter—is desired a fireproof composition, such as lignolite or any other fireproof material, may be used as a filler. In fireproof structures greater security may be obtained by protecting the narrow neck 7, joining the rib 1 to the body of the strip, by extending one of the inturned ribs—as, for instance, the rib 2—farther down or beyond the other, thus covering the said neck. The strips are capped at the ends by means of caps 8, properly secured, and the rib of each strip may be cut away, forming a notch 9, as shown in Fig. 3, to receive the cap of the connected strip to thereby prevent the strips from sliding longitudinally independent of each other, or any other suitable means may be employed for this purpose.

Without limiting myself to the precise construction and arrangement shown, I claim—

1. The combination in a flexible screen, of strips each hollow and provided with a filler and with a rib 1 at one edge and parallel inturned ribs at the other edge adapted to engage the rib 1 of the next strip and constituting the sole means of connecting the two, substantially as set forth.

2. The combination in a flexible screen, of strips each hollow and provided with a filler and with a rib 1 at one edge and parallel in-turned ribs at the other edge adapted to engage the rib 1 of the next strip and constituting the sole means of connecting the two, and caps closing the ends of the hollow strips, substantially as set forth.
3. The combination in a flexible screen, of strips each hollow and provided with a fire-proof filler and with a rib 1 at one edge and parallel in-turned ribs at the other edge adapted to engage the rib 1 of the next strip and constituting the sole means of connecting the two, substantially as set forth.
4. The combination in a flexible screen, of strips each with a cylindrical rib at one edge and with separated hollow in-turned ribs at the opposite edge adapted to engage the cylindrical rib of the next strip, and a bent strip fitting said hollow ribs, substantially as set forth.
5. A metallic screen consisting of strips jointed together to form a continuous flexible self-supporting and connecting structure, each strip with a cylindrical rib at one edge and with in-turned ribs at the opposite edge enga-
- gaging the cylindrical rib of the adjacent strip, one inturned rib extending below the edge of the other, substantially as and for the purposes set forth.
6. A metallic screen consisting of hollow strips containing fireproof filling jointed together to form a continuous flexible self-supporting and connecting structure, each strip with a cylindrical rib at one edge and with in-turned ribs at the opposite edge engaging the cylindrical rib of the adjacent strip, substantially as set forth.
7. A metallic screen consisting of strips jointed together to form a continuous flexible self-supporting and connecting structure, each strip with a cylindrical rib at one edge and near one side, and with in-turned ribs at the opposite edge engaging the cylindrical rib of the adjacent strip, substantially as set forth.
- In testimony whereof I have signed my name to this specification in the presence of two subscribing witnesses.

PERCY HUNT WILSON.
